UNITED STATES PATENT OFFICE

JOSEPH GOULDBOURN AND REGINALD BOYD WOODCOCK, OF LEICESTER, ENGLAND,
ASSIGNORS TO UNITED SHOE MACHINERY CORPORATION, OF PATERSON, NEW
JERSEY, A CORPORATION OF NEW JERSEY

MACHINE FOR OPERATING ON WELTING

Application filed April 22, 1921; Serial No. 463,673, and in Great Britain July 21, 1920. Renewed
January 12, 1929.

In the manufacture of welted boots and shoes, it is customary to beat out the welt after the welt has been secured to the upper and insole, in order to cause it to lie flat in substantially the plane of the insole. As the sidewise deflection of the welt in applying it to the toe portion of a shoe, particularly a pointed toe shoe, causes the welt to curl or turn up at the toe, this portion of the welt is usually provided with a series of cuts or slashes in its flesh side to enable the outer edge thereof to stretch sufficiently during the beating out operation to bring it into the plane of the insole. It has been found to be advantageous to thus slash the welt before or at the time that it is being sewed to the upper and insole and, accordingly, it has been proposed to apply a welt-slashing mechanism to the welt sewing machine in such a manner that the welt may be slashed in advance of the stitch forming devices. In order that such welt-slashing mechanism shall require but a minimum amount of care and attention on the part of the operator, it has been proposed to so construct the welt-slashing mechanism that when thrown into operation it will form a predetermined number of slashes in the welt and then cease to act during the continuation of the sewing and until again thrown into operation. Different classes of work, however, require a different number of slashes to be made in the welt and such prior mechanisms have no provision for thus varying the slashing operation.

Accordingly, an object of the present invention is to improve mechanisms of this type for operating on a welt, particularly with a view of overcoming the disadvantage above described of said prior constructions.

With this object in view a feature of the present invention contemplates the provision in a machine employed in the manufacture of shoes having welt attaching means of mechanism for operating on the welt in advance of the attaching means; timing devices for throwing said mechanism out of operation at the completion of a predetermined period of operation thereof; and means for adjusting the timing devices to vary the length of such period of operation of said mechanism.

While this feature of the invention in its preferred form is particularly adapted for use in a welt-slashing mechanism for a Good-year welt shoe sewing machine, it is to be understood that, except as defined in the claims, this feature of the invention is not limited to such use, as, obviously, it may include other shoe machines having welt attaching means and also mechanisms other than welt slashing mechanisms for operating on a welt in advance of the welt attaching means.

Other features of the present invention consist in certain constructions, arrangements and combinations of parts hereinafter described and claimed, the advantages of which will be obvious to those skilled in the art.

The several features of the invention will be clearly understood from the following description and accompanying drawings, in which:

Figure 1 is a perspective view of part of a welt sewing machine of the type disclosed in Patent No. 1,108,560, dated August 25, 1914, showing a preferred form of welt-slashing mechanism in an operative position.

Figure 2 is a side elevation, partly broken away, of the welt-slashing and counting mechanism in inoperative position.

Figure 3 is a sectional plan view showing the welt guide and slashing knife; and

Figure 4 is a part sectional elevation of part of the counting mechanism.

In this illustrative embodiment of the invention, the welt guide 3 is supported and actuated in the manner illustrated and described in the patent hereinbefore referred to, being supported on one end of a semi-circular arm 5 of radius greater than the curved hooked needle and pivoted eccentrically to the needle. The welt guide receives the welt strip passing to it about the usual drum 6 of the welt measuring mechanism and positions it as is well understood while it is being secured to the shoe by the agency of the usual curved hooked needle actuated by the needle lever 7, the shoe being positioned by the shoe gauge 8 and fed step by step by the awl 9.

The welt guide is extended rearwardly to form a guideway 10 for the knife bar 11 on

the forward end of which is formed the knife 12. The knife is reciprocated in the welt guide by a link 13, one end of which is pivotally connected at 15 to a block 17 which is 5 clamped on the knife bar and which slides in the guideway 10. The link is connected at its other end to the upper end of a vertically disposed lever 19 pivoted to a bracket 21 fast on the machine frame. The lower end of this 10 lever has pivotally connected to it at 23 one end of a link 25, the opposite end of which is pivotally connected at 27 to the lower end of a lever 29. This lever is pivotally connected at its upper end to one arm of a cam 15 lever 31 pivoted on the machine frame and operated by a cam 33 which has been cut in the cam disc in which is already provided the cam 35 for moving the channel guide 37 to and from the work through the agency of 20 the lever 39 and the customary associated mechanism. The lever 29 has a downward extension 41 at its lower end which is guided between a face formed on a bracket 43 fixed to the machine frame and a plate 45 screwed to 25 the bracket. The lever 29 has near the centre of its length a roll 47 which, when the slashing mechanism is in operation, is confined between the end of a plate 49 fast on the bracket 43 and the end of one arm 51 of a bell-crank lever pivoted on the bracket 43, the lever 29 then moving about the axis of 30 the roll 47. When the end of the lever arm 51 is moved away from the roll the lever 29 rocks idly about its pivotal connection 27 to 35 the link 25 and the slashing knife is out of operation. The slashing knife when out of operation is held rearwardly out of the welt guide by a spring 53 fastened at one end to the link 25 and at the other end to a pin fixed 40 in the machine frame. The lever arm 51 has formed on one side a lug 55 which when the slashing mechanism is out of action rests on a second lug 57 formed on a vertically disposed arm 59 of a second bell-crank lever also 45 pivoted on the bracket. The other arm 61 of the second bell-crank lever is connected by a rod 63 to a knee lever. A spring 65 the ends of which are connected to the arm 51 of the first bell-crank lever and to the arm 61 50 of the second bell-crank lever, respectively, acts to move the arm 51 into position where its end engages the roll 47 when the knee-lever is pressed by the operator and also tends to return the second bell-crank lever when 55 the knee-lever is released. When the arm 51 of the first bell-crank lever is thus engaged with the roll 47 the second bell-crank lever is prevented from returning to normal inoperative position upon releasing the knee 60 lever, by the engagement of a side of the lug 57 with the lug 55. The second bell-crank lever is permitted to be returned by the spring 65 to its normal inoperative position when the arm 51 of the first bell-crank lever 65 is swung upwardly away from the roll 47 by means hereinafter described, such movement of the arm 51 causing the lug 55 to be raised out of engagement with the side of the lug 57. The arm 51 of the first bell-crank lever has on it a face 67 which engages a stop face 70 69 on the bracket 43 when the arm is released to engage the roll. The lever 19 has pivotally connected to it near its lower end, one end of a connecting rod 71 which operates the counting and throw-out mechanism. The 75 other end of this rod is pivotally connected to a lever 73 fulcrumed on a horizontal shaft 75 which is supported in the bracket 43 aforementioned. The lever carries a pawl 77 which is held by a spring 79 in engagement 80 with a ratchet wheel 81. A second pawl 83 pivoted on the bracket and yieldingly held in engagement with the ratchet wheel, prevents return movement of the ratchet wheel. The ratchet wheel is mounted on a sleeve 85 portion 85 of a cylindrical member 87 and is pinned to the member. The member is rotatably mounted on the shaft 75 and is recessed to receive a clock-spring 89 one end of which is connected to the cylindrical member 90 and the other end to a pin 91 which projects into the recess from a disc 93 which is also rotatably mounted on the shaft. The disc 93 has notches 95 in its periphery, the number of notches coinciding with the number of teeth in the ratchet wheel 81. The disc 93 is held in any desired position, for the purpose, as will hereinafter be described, of determining the number of slashes to be cut, by a latch 97 pivoted on the bracket and held 100 in engagement with one or the other of the notches in the disc by a spring-pressed plunger 99 mounted in the bracket. The disc 93 has extending from its side adjacent the cylindrical member a stop lug 101 against which a projection 103 on the cylindrical member is held by the clock-spring 89 when the slashing mechanism is out of action. The member 87 and with it the projection 103 are rotated during slashing, the space of one 105 tooth for each cut until, after the desired number of slashes have been cut, the projection 103 encounters the other arm 105 of the first mentioned bell-crank lever and turns this lever about its pivot to remove the end 110 of its arm 51 away from the roll 47 on the lever 29 which then rocks idly on its lower pivot, the slashing mechanism thus being thrown out of action. The arm 59 is so formed at its upper end that when the knee 115 lever is released the return of the bell-crank by its spring 65 releases the pawls 77, 83 from the ratchet wheel and allows the clock-spring to return the cylindrical member until the projection 103 encounters the stop lug 101 on the disc 93. The mechanism will then on the next actuation of the knee lever, cut the same number of slashes and be automatically thrown out of action. The 120 notches in the disc are numbered to corre- 125 130

spond with the number of slashes which will be cut for a particular setting of the disc and a pointer 107 is provided on the bracket and index marks opposite the notches whereby the disc may be readily set to give a desired number of slashes from one upwards.

In the construction herein detailed the movement of the ratchet wheel, cylindrical member and its projection 103 takes place during the return movement of the slashing knife, so that the throwing out of action of the slashing knife occurs after the last cut is made thereby ensuring that the last cut is fully and correctly effected.

It will be appreciated that the two bell-crank levers are to such a degree independent in their movements that should the operator still maintain the pressure on the knee lever at the time the projection 103 on the cylindrical member meets the arm 105 of the first bell-crank lever the free movement of the latter will not be interfered with and it will be necessary for the operator to release the knee lever before a second series of slashes can be effected.

Furthermore the notched disc can be set so that the projection 103 on the cylindrical member is holding the first bell-crank lever clear of the roll 47 with the result that movement of the knee lever will be without result on the knife actuating mechanism.

While the features described above are well adapted for use in the welt shoe sewing machine illustrated in the drawings, it is to be understood that, except as defined in the claims, certain features of the invention are not limited to use in a machine of this type, as they may be used in other machines for operating on welting, whether or not the welting is of the type used in Goodyear welt shoes.

The nature and scope of the present invention having been indicated and a machine embodying the several features of the invention in their preferred form having been specifically described, what is claimed is:—

1. A machine for operating on welting having, in combination, a welt slashing knife, mechanism for advancing and retracting the slashing knife across the welt to make slashes in the welt, timing devices acting automatically after a predetermined number of slashes have been made in the welt to throw said mechanism out of operation and means for actuating said devices during the retracting movement of the welt slashing knife.

2. A machine for operating on welting having, in combination, welt slashing mechanism, means comprising a controlling member rotating step by step in one direction during the operation of said mechanism for throwing said mechanism out of operation after a predetermined number of degrees of rotation of the controlling member, and

means for rotating the controlling member in the reverse direction to return the controlling member to its initial position when said mechanism is thrown out of operation.

3. A machine for operating on welting having, in combination, welt slashing mechanism, means comprising a constantly oscillating lever for actuating the welt slashing mechanism capable of being controlled to oscillate about either of two axes, and means for controlling such oscillating movements of the lever to throw the welt slashing mechanism into and out of operation.

4. A machine for operating on welting having, in combination, mechanism for making a predetermined number of slashes in a welt when thrown into operation, devices under the control of the operator for throwing said mechanism into operation, and means capable of being adjusted by the operator to prevent said mechanism from being thrown into operation upon operation of said devices.

5. A machine for operating on welting having, in combination, welt slashing mechanism, devices under the control of the operator for throwing said mechanism into operation, and timing means for the welt slashing mechanism for controlling the number of slashes made in the welt capable of being adjusted by the operator to prevent said mechanism from being thrown into operation upon operation of said devices.

6. A machine for operating on welting having, in combination, welt slashing mechanism, means comprising a controlling member moving in one direction during the operation of said mechanism for throwing said mechanism out of operation after a predetermined movement of the controlling member, and means for moving the controlling member in the reverse direction to return the controlling member to its initial position.

7. A machine for operating on welting having, in combination, welt slashing mechanism, means comprising a controlling member moving in one direction during the operation of said mechanism for throwing said mechanism out of operation after a predetermined movement of the controlling member, means for moving the controlling member in the reverse direction to return the controlling member to its initial position, and an adjustable stop to determine the initial position of the controlling member.

8. A machine for operating on welting having, in combination, welt slashing mechanism, means comprising a controlling member moving during the operation of said mechanism for throwing said mechanism out of operation after a predetermined movement of the controlling member, and means for moving the controlling member to its initial position after the welt slashing mechanism is thrown out of operation.

9. A machine for operating on welting having, in combination, welt slashing mechanism, means comprising a controlling member moving during the operation of said mechanism for throwing said mechanism out of operation after a predetermined movement of the controlling member, means for moving the controlling member to its initial position after the welt slashing mechanism is thrown out of operation, and means for adjusting the initial position of the controlling member.

10. A machine for operating on welting having, in combination, welt slashing mechanism, a member operable by the operator and acting when moved by the operator during the operation of the machine to throw said mechanism into operation, and means acting automatically to throw said mechanism out of operation after a predetermined number of slashes have been made in the welt and while the member remains in the position to which it has been moved by the operator.
